Attorney

UNITED STATES PATENT OFFICE.

EUGENE C. KUBIK, OF ST. LOUIS, MISSOURI.

DUSTBRUSH FOR PENCILS.

1,386,635.

Specification of Letters Patent. Patented Aug. 9, 1921.

Application filed July 26, 1919. Serial No. 313,456.

To all whom it may concern:

Be it known that I, EUGENE C. KUBIK, a citizen of the United States, residing at St. Louis, in the city of St. Louis and State of Missouri, have invented certain new and useful Improvements in Dustbrushes for Pencils, of which the following is a specification.

In the ordinary use of marking pencils, it is frequently necessary to erase the marking and this operation results in the formation of dust which usually is removed from the surface either by blowing the breath thereon or passing the hand thereover. Both of these methods are unsanitary and otherwise objectionable and the present invention aims to provide a brush which is attached to the pencil in a unique manner and which serves as means to prevent the pencil from rolling when placed upon a slanting desk or table.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

Referring to the accompanying drawings which illustrate the invention applied;

Figure 1 is a front view of the end portion of a lead pencil provided with a dust brush attached thereto in accordance with the invention.

Fig. 2 is a side view of the parts illustrated in Fig. 1.

Fig. 3 is a top plan view of the pencil.

Fig. 4 is a sectional detail on the line 4—4 of Fig. 1.

Fig. 5 is a detail section on the line 5—5 of Fig. 3; and

Fig. 6 is a detail perspective view of the brush holder.

Corresponding and like parts are referred to in the following description and indicated in the several views of the drawings by like reference characters.

The numeral 1 designates a lead pencil of ordinary construction, the same being provided at one end with a metal sleeve 2 and an eraser 3 which consists of a block of rubber.

In accordance with the present invention,

a brush 5 is secured to the pencil by means of a holder 4 which is provided with a shank 6, which is inserted within the outer portion of the sleeve 2 and retained therein by means of the eraser 3. As shown most clearly in Fig. 5 the sleeve 2 is provided with a punch mark 7 which is disposed opposite the shank 6 and deflects said shank, thereby materially assisting in retaining the holder in position. The dust brush usually consists of a plurality of bristles or elements arranged to form a tuft which is engaged at a middle point by means of the holder, thereby providing in effect a double ended brush which is arranged crosswise of the pencil. This results in the provision of means to prevent the pencil from rolling when placed on a slanting table or desk. Moreover, by providing a double ended brush, greater convenience results over the provision of a single brush, because one of the brush ends is usually in convenient position for use without requiring the shifting or moving of the pencil to bring a brush end in position for service when it is required to remove dust from a surface.

The holding preferably consists of a metal strip having an end portion rolled upon itself to snugly embrace the brush and confine the elements thereof. The opposite end of the strip is folded upon itself to produce a shank 6 of hook form which embraces a portion of the outer end of the sleeve 2, the shank 6 being confined within the sleeve by means of the eraser 3 which is pressed into the sleeve in a manner well understood.

The invention is particularly adapted for lead pencils intended for office use and when markings are erased, the dust produced may be easily and quickly removed from the surface by use of the brush, as will be readily understood. The sleeve 2 may be of any length and constitutes a hollow support for the brush and eraser, the shank 6 of the brush holder being retained in place by means of the part 3 which serves as a plug.

The foregoing description and the drawings have reference to what may be considered the preferred, or approved form of my invention. It is to be understood that I may make such changes in construction and arrangement and combination of parts, materials, dimensions, et cetera, as may prove ex-

pedient and fall within the scope of the appended claims.

Having thus fully described my invention, what I claim as new and desire to secure by Letters Patent is:

- 5 1. In combination, a hollow support, a holder having a shank inserted in the support and a plug within the support for retaining the shank therein and brushing elements carried by the holder.
- 10 2. In combination, a hollow support having a lateral indentation forming an inner projection, a holder having a shank disposed within the support and receiving the same inner projection, an elastic plug closing the end of the support and retaining the said shank in the required position and brushing elements carried by the holder.
- 15 3. In combination, a hollow support, a strip having one end constituting a holder and having the opposite end inserted in the support, a plug securing the end of the strip within the support and brushing elements carried by the strip.
- 20 4. In combination, a sleeve, a handle inserted in one end of the sleeve, an elastic plug inserted in the opposite end of the sleeve, a holder having a shank disposed within the end of the sleeve receiving the
- 25 30 plug and retained therein by means of the

plug and brushing elements carried by the holder.

5. In combination, a hollow support, a holder having a shank inserted in the support, means within the support for retaining the shank therein and brushing elements carried by the holder.

6. In combination, a hollow support having a lateral indentation forming an inner projection, a holder having a shank inserted within the support and receiving the same inner projection, means closing the end of the support and retaining the shank in the required position, and brushing elements carried by the holder.

40 7. In combination, a hollow support, a strip having one end constituting a loop and having the opposite end inserted in the support, means securing the end of the strip within the support, and brushing elements carried within the loop of the strip so as to extend transversely of the hollow support.

45 In testimony whereof I affix my signature in presence of two witnesses.

EUGENE C. KUBIK.
